H. A. MANKAMEYER

SELF CLOSING CASE

Filed March 15, 1924

Inventor:
H. A. Mankameyer,

By H. L. Woodward,

Attorney

UNITED STATES PATENT OFFICE.

HARRY A. MANKAMEYER, OF KANSAS CITY, MISSOURI.

SELF-CLOSING CASE.

Application filed March 15, 1924. Serial No. 699,549.

To all whom it may concern:

Be it known that I, HARRY A. MANKAMEYER, a citizen of the United States, residing at Kansas City, in the county of Jackson and State of Missouri, have invented certain new and useful Improvements in Self-Closing Cases, of which the following is a specification.

The invention has for an object to effect improvements in closure operating devices particularly suited to use in sign displaying cases having hinged doors. An important object of the invention is to provide a desirable case suitable for displaying on the exterior of a building the cards exposed by householders so as to be viewed from the street by venders, to signify when a particular commodity is desired, so that when such a vendor passes he will stop and deliver his product. The device aims to provide a construction which will insure protection of paper cards against the weather and dirt, while at the same time permitting the removal and insertion of such cards as may be desired, or the change of position of cards in the device from concealed to display position.

It is a specific object of the invention to present a novel spring closure operator which is readily assembled, which is liable in a minimum degree to impairment casually or by wear and deterioration. It enables the production of the device by the use of stock materials involving inexpensive machine operations for its formation, and no assembly at the factory in its preparation for sale. At the same time it enables the use of a high grade of material with a low cost for fabrication in the resilient element and its heat treatment.

The invention also aims to present a spring closer adapted to be assembled in a novel manner, and enabling the release of the door or other element from its action without removal of fastenings, and without requiring special movable securing devices to hold the parts in engaged and disengaged relations.

Additional objects, advantages and features of invention reside in the construction, arrangement and combination of parts as may be understood from the following description and accompanying drawings in which—

Figure 1 is a front elevation of a case

constructed in accordance with my invention.

Figure 2 is a perspective of the empty case, open.

Figure 3 is a vertical cross section of the device. 60

Figure 4 is a similar view showing the device opened.

Figure 5 is a fragmentary section on the line 5—5 of Figure 3. 65

Figure 6 is a detail cross section of the spring guide.

Figure 7 is a plan of the blank for the guide.

There is illustrated a case 10 with a hinged cover 11 glazed for observation of the contents of the case. The case body is ordinarily formed of No. 20 gauge sheet metal, and includes a back 12 and integral sides 13 and top 14 and bottom 15. In fabricating the body from its blank the bottom is formed with ears 16 which are turned inward within the sides 13 and soldered thereto and these overlapped portions are apertured to form a bearing for a hinged rod or rivets indicated at 17. 70

The cover is a rectangular frame, including side and top members 18 and 19 and a bottom member 20, each member being L-shaped in cross section, providing outer flanges 21 on the top and sides fitting snugly over corresponding parts of the body of the case, and inner glass mounting flanges 22 of familiar form forming the front side of the cover. The bottom member 20 is provided with an apron flange 23 corresponding to the outer flanges of the other parts, but arranged to lie within the case. For this purpose it is not connected with the adjacent outer flanges, slots 24 being formed 80 between the bottom member and the flanges 21 at each side, the slots extending also a short distance into the parts 22 immediately adjacent the flanges 21, which thus project at the lower part of the cover as ears 25 beside the case body, and have the hinge pivot elements 17 engaged therein. The cover is thus permitted to open without obstructive interference between its parts and the case body, while at the same time presenting a 85 snug closure. The flange 23 may be set so as to resiliently press against the bottom 15 when in closed position, and automatically form a snug, tight closure. It is preferably 90

also extended so as to lie very close to the 100

110

back 12 of the case body when in closed position, and thus form a rest for any large cards which may be introduced into the device. The cover is provided with a hand 5 knob 26 for opening and closing the case. Fixed in the case body, one at each side, and preferably on or immediately adjacent the back 12 and close to the hinge axis of the cover, there is a guide sleeve 27, while 10 a second sleeve 28 at each side is fixed upon the cover preferably on or immediately adjacent the front or glass mounting flanges 22, and movable with the cover in a plane with the medial line of the corresponding 15 sleeve 28, and alined with that plane. The sleeve 28 is preferably midway between the the sleeve 27 and the top of the case when closed. Set loosely in these sleeves there is a plain strap or leaf spring 29, tending to 20 assume a rectilinear form, and its ends project beyond the sleeves when the device is in closed position. On opening movement of the cover the lower or sleeve 27 tends to hold the spring against withdrawal so that 25 its upper end portion moves slidably in the sleeve 28. The spring is preferably of such a length that when moved longitudinally toward the upper part of the case while in partly open position, its lower end will be 30 drawn from the sleeve 27 and thus permit its removal.

The sleeves 27 and 28 are formed so as to receive the spring very loosely, which facilitates the removal and replacement of the 35 spring when required, enabling ready cleaning of the device, as well as making for ease in assembly during manufacture of the case. A stop 30 may be provided on the cover in line with the sleeve 28, at a position to check 40 longitudinal movement of the spring and to hold it in position to be properly retained in the sleeve 27. The sleeves 27 and 28 may comprise simple blanks 29 having opposite edge portions bent inward in opposed relation 45 and spaced relation to the intermediate part of the blank, and for convenience in assembly by soldering; the blank may have projections 27 at the corners arranged to extend longitudinally of the finished sleeve. 50 These afford tongues by which the sleeves may be quickly soldered to the case, enabling

direct contact of an iron with the part of the sleeve to be attached. The sleeves may be variously formed, and the spring also, as will be understood. 55

It will be seen that when the cover is opened, the spring will be bent into an ogee shape, the bend at each end increasing with the extent of opening movement. The outer end portion will tend to slide while the inner part will tend to be retained in the sleeve 27, although some slip may occur. It is immaterial which end develops the sliding movement, as the spring is adjusted so that it will not be withdrawn at either end on normal opening movement, no matter which end slips. The stress causing the spring to overcome the strain set up will cause it to straighten out when the closure is released and its ends moving slidably in the sleeves 70 will draw the case body and cover into closed relation. 60

I claim:

1. A case and a closure therefor movable to and from closed position, a leaf spring 75 element, a mounting for the spring comprising a bearing on the case and another bearing on the closure each having the spring slidably engaged therein and being spaced apart longitudinally of the spring when the 80 cover is in closed position.

2. In devices of the character described, two members mounted for movement toward and away from each other, respective guide 85 devices thereon, a leaf spring element slidably engaged therein, said guide devices embracing the spring and being spaced longitudinally of the spring element and from each other when the relatively movable members are in closest proximity. 90

3. In a closure operating device, a closure mounting, a closure movable thereon, a leaf spring and guide devices on the mounting and closure respectively, end portions of the spring being slidably engaged with said 95 guides, and tending to assume a rectilinear form in opposition to opening movement of the closure whereby, under separation of the closure and mounting, the spring will be bent increasingly in an ogee shape. 100

In testimony whereof I affix my signature.

HARRY A. MANKAMEYER.
